MANIFOLDING CHECKBOOK

James C. Shepherd, Longview, Wash., assignor, by
direct and mesne assignments, to Universal
Business Forms, Inc., a corporation of Oregon

Application October 15, 1951, Serial No. 251,319

4 Claims. (Cl. 282—23)

1

This invention relates to a manifolding set and more particularly to an improved check and voucher arrangement.

It is an object of this invention to provide a new and convenient check and voucher arrangement.

It is a further object of this invention to provide means for obtaining a record of the essential data upon the making of a check.

It is a further object of this invention to provide check vouchers readily adapted for accounting of expenditures made by check.

It is a still further object of this invention to provide a unitary check and voucher easily and simply made.

Other objects and advantages of the present invention will be apparent from the following description. In accordance with the illustrated embodiments, the present invention consists of a check provided with a voucher to receive in duplicate the payee, date and amount of check. The check is of the usual rectangular form and the designated areas for the above-mentioned data are included within approximately the upper longitudinal half of the check. This data is transferred to the voucher by means of a transfer sheet having a pressure-sensitive transfer surface thereon interposed between the check and the voucher. In cooperation with the space for receiving the amount of the check, indicia and space are provided on the voucher for computing the balance of the account upon which the check is drawn. In the lower longitudinal half of the voucher a record column is imprinted extending longitudinally of the voucher. A list of items including the most likely items for which expenditures are made is imprinted in the column with space adjacent each item for distributing the expenditure made by a check to the proper account or accounts. The side edge of the voucher lying at the top of the record column has a series of perforations adapting the voucher for use with the peg book which forms the subject of applicant's copending application, Serial No. 248,235, filed September 25, 1951, now U. S. Patent No. 2,635,608, issued April 21, 1953.

This peg book is provided with a long, straight row of pegs spaced at the same intervals as the perforations in the side edge of the voucher. At the end of each month or other selected accounting period the vouchers accumulated in that period are shingled on this row of pegs with only the figures in the record column exposed. The horizontal rows of figures are then totaled and entry is made in a summary sheet placed on the

2

peg book below the vouchers. A check, its voucher and its transfer sheet are made up from a single sheet of paper by suitably preparing selected portions of a sheet to conform to one of the desired items and folding the sheet so that the check portion lies superposed the voucher portion of the sheet with the portion forming the transfer sheet lying between them. Lines of separation are provided through the sheet so that the portions may be separated from one another. For convenience in handling, a number of the folded sheets can be bound together to form a checkbook.

In the drawings, Fig. 1 is an end elevation of the check and voucher arrangement of the present invention; Fig. 2 is a view in perspective of a checkbook with the check and vouchers of the present invention assembled therein, the uppermost unit of which is opened up to show a preferred arrangement of this invention; Fig. 3 is a plan view of the voucher of this invention; Fig. 4 is a plan view of a number of vouchers of this invention arranged for the accounting of expenditures recorded on the vouchers; Fig. 5 is a view in perspective of a modified form of the present invention; Fig. 6 is a perspective view of an adaptation of the check and voucher illustrated in Fig. 1 partly opened to show the arrangement of various parts; and Fig. 7 is a plan view of a detail of Fig. 6.

Referring now to the drawings, there is pictured in Fig. 1 a voucher 11 which has superposed thereon a check 10 with a transfer sheet 12 interposed between the check and the voucher. Check 10 is provided with the usual indicia thereon as shown in Fig. 2. For the purposes of the present invention it is preferable that the designated space for the date, the payee and the numerical figures of the amount of the check be located on the upper longitudinal portion of the check as shown in Fig. 2.

The voucher 11 pictured in Fig. 3 has designated space thereon for receiving an impression of the date, the payee of the check and the numerical figures of the amount. These areas are located on the voucher so that they will be in register with the pertinent areas of the superposed check. Additional indicia is provided on the voucher for computing the balance of the account, there being provided space for the balance brought forward from the preceding check, deposits, and summarizing space in cooperation with the area which will contain an impression of the numerical amount of the check. In the lower portion of the voucher there is imprinted

thereon a record column 13 having one portion thereof devoted to a list 14 of items for which expenditures are most frequently made, and a further portion of the column is provided with spaces 15 for recording therein the amount of the check against the item for which the expenditure is made. A few blank spaces 16 are provided in the column for writing in expenditures for unusual items not included in the imprinted list. The side edge of the voucher 11 which lies at the top of the record column 13 is provided with a series of perforations 17, the purpose for which will be more fully explained subsequently.

To obtain an impression of the payee, date and the numerical amount of the check on the voucher, the transfer sheet 12 is provided with a pressure-sensitive transfer medium 18 such as a carbonized layer or the like on the surface of the transfer sheet which will lie adjacent the voucher. The transfer medium 18 is distributed over sheet 12 so that it will lie under only the pertinent portion of the check whereby incidental data such as the written amount of the check and the maker will not be impressed upon the voucher, such information not being necessary for most record-keeping purposes and especially for the ends of this invention.

The arrangement of the various portions allow for convenient preparation from a single sheet of paper of the check, voucher and transfer sheet by preparing suitable portions thereof in a required manner and folding the sheet as shown in Figs. 1 and 2, that is, along line 19 dividing the check and voucher and along line 20 dividing the check and transfer sheet. To facilitate separation of the various portions from one another, a line of severance 21 is provided along fold line 19 and a line of severance 22 is provided along fold line 20. The individual sheets are conveniently prepared for binding a plurality in a check book form depicted in Fig. 2 by leaving a base portion 23 extending from voucher 11 and securing a plurality of sheets together with rings 24 through the base portion 23. A line of severance 25 is provided through the sheet along a line separating the base portion of the voucher so that the voucher may be detached from the bound base portion.

The check of this invention is made out in the usual manner and as indicated above an impression is obtained on the voucher of the payee, the date and the amount of the check. After making out the check, the transfer portion 12 is detached from the check 10 and the check detached from the voucher 11, allowing the check to be distributed in the usual form. The amount of the check appearing on the face of the voucher can then be distributed to the items in record column 13 for which the expenditure made by the check should be attributed. After distribution of the expenditures and detaching it from the base, the voucher is adapted to be assembled with a number of other vouchers representing various expenditures for ready accounting. This feature is best illustrated in Fig. 4.

In Fig. 4, numeral 27 designates a leaf of an accounting peg book which forms the subject matter of my copending application, *supra*. Leaf 27 is provided with a number of upstanding pegs 28 along the top edge thereof with a summary sheet 29 leaved upon pegs 28 in the manner shown. Sheet 29 contains monthly summary columns such as 30 and 31 for each month of the year, a total summary column for the year (not

shown), and a list of items 32 corresponding to list 14 on voucher 11. Each month the vouchers for the checks written that month are shingled in the manner shown, that is, with the first laid down immediately to the left of the monthly column to be filled in and each succeeding voucher leaved upon the next with only the amount figures in column 15 of each voucher showing. The expenditures for each month can then be totaled by adding the horizontal item columns and recording in the monthly column the total expended that month for the particular item.

Fig. 5 illustrates another embodiment of the present invention. The check book 40 illustrated therein is made up of a plurality of sheets bound with staples 41. Each of the individual sheets includes a top transfer section 42, a central voucher section 43 and a bottom check section 44. As is shown, the sheet is folded along a line 46 parallel to the top edge 45 so that the transfer section 42 lies superposed of a portion of the voucher 43. The staples 41 pass through the folded sheet in close proximity to the fold line 46. A line of severance 47 is provided through the sheet so that the top section may be detached from the bound portion of the sheet and a line of severance 48 is provided so that voucher 43 may be separated from the bound portion. The sheet is further folded along line 49 whereby the check section 44 lies superposed of the voucher 43 with the transfer section 42 interleaved between the check and the voucher with a line of severance 50 provided through the sheet along the fold line 49 whereby the check may be detached from the voucher. As illustrated, suitable indicia is provided on the face of the check.

The voucher 43 is imprinted in the manner of the voucher 11 illustrated in Fig. 3. To secure an impression of the payee, date and amount of the check on the voucher, the transfer section 42 is provided with a pressure-sensitive transfer medium 51 such as a carbonized surface or the like on the surface which lies adjacent to the voucher over the portion underlying the pertinent parts of check 44. The manner of using this form of the invention is substantially the same as previously explained; and, of course, the voucher is preferably supplied with a perforated side edge so that it may be utilized with the peg book of copending application, *supra*.

In another modification of the present invention the record column may be imprinted on the reverse side of the voucher and the entire face of the voucher devoted to receiving a duplicate of the check. Also, indicia may be provided on the reverse side of the voucher for noting cash receipts and expenditures.

In Fig. 6 is illustrated the manifolding check and voucher of this invention in a form adapted for business uses. For convenience and clarity the assembly is shown in a partially unfolded condition. As shown therein a rectangular paper sheet 60 is provided with a line of severance 61 extending across the sheet parallel to one side edge thereof and dividing the sheet into major and minor portions. The sheet is further divided into a duplicate section 62, an original section 63 and a transfer section 64, each extending across the sheet normal to the line of severance 61. As shown, the individual sections are so located and the sheet folded whereby the original section 63 lies superposed the duplicate section 62 with the transfer section 64 interleaved between the original and duplicate sections.

The major portion 70 of the original section

5

is provided with check indicia, preferably with the designated space for the date, the payee, and the numerical figures of the amount located within the upper longitudinal portion of the check, as shown in Fig. 6. The minor portion 71 of the original section is imprinted as a payroll tab with appropriate indicia for indicating such items as withholding tax, social security, and other deductions, and such other indicia as is deemed appropriate for the particular enterprise for which payment is being made.

The arrangement of the duplicate section 62 is best shown in Fig. 7. As shown therein, the major portion 75 of the duplicate section is arranged as a voucher 11 illustrated in Fig. 3. The upper longitudinal portion of major portion 75 is provided with designated space in registry with the corresponding spaces of the check for receiving an impression of the date, the payee of the check, and the numerical figures of the amount. Additional indicia is also provided for computing the balance of the account, there being provided space for the balance brought forward from the preceding voucher, deposits, and summarizing space incorporated with the area which will contain an impression of the numerical amount of the check. In the lower portion of the voucher there is imprinted a record column 76 having one section thereof devoted to a list of items 77, for which expenditures are most frequently made, and a further section of the column provided with spaces 78 for recording therein the amount of the check against the item for which the expenditure is made. The side edge of the voucher 75 which lies at the top of the record column 76 is provided with a series of perforations 79 whereby the voucher is adapted for shingling with other vouchers in the manner described above.

The minor portion 82 of the duplicate section 62 is imprinted as a substantial duplicate of original payroll tab 71, the corresponding indicia and areas being in registry with one another.

The transfer section 64 is provided with a pressure-sensitive transfer medium 85 on the surface of the transfer section which will lie adjacent the duplicate section. The transfer medium 85 is preferably distributed over the transfer section 64 so that it will lie under only the pertinent portions of the check and original payroll tab, thus incidental data not necessary for the record keeping purposes will not be impressed upon the voucher or the duplicate payroll tab.

The adaptation illustrated may be easily prepared from a single sheet of paper by imprinting suitable portions of the sheet and folding it as illustrated in Fig. 6; that is, along line 88 dividing the original and transfer sections and along line 89 dividing the original and duplicate sections. To facilitate separation of these sections from one another, a line of severance is preferably provided through the sheet along each of the fold lines 88 and 89. By providing duplicate section 62 with projecting tabs 90 having perforations 91, the sheets are adapted for securing a number together with rings or other binding means passed through the perforations 91. Preferably the sheet is provided with a line of severance 92 between the duplicate section and the projecting tab 90 to facilitate separation of the duplicate section from the binding.

In the particular form of the invention just described above it is intended that the entire original section 63, that is, the check and the

6

original payroll tab, be given to the employee; the duplicate section is to be retained by the maker of the check. The voucher 75 may be used in the manner previously alluded to, while the detachable payroll tab may be conveniently assembled with other tabs, as by pasting on a sheet, to keep a separate payroll record as is frequently desired.

In using the check book, it is advantageous to start with the check lowermost in the book. In this manner an impression is not formed upon the lower voucher, inasmuch as upon making of each check the carbon is dispensed with. This system possesses a number of advantages which should be readily apparent. As can be seen, there is no portion of the figures indicating the maker's account condition exposed to view while he makes out his check, inasmuch as the check covers the face of the voucher whereon are recorded any figures of deposits and balance, and the maker of the check may keep these matters confidential, with no fear of exposure. However, such figures are readily available to him from the next lower preceding voucher when he needs them.

An important advantage of this invention is that the maker of a check cannot through haste or negligence fail to record the amount and payee of a check, since it is automatically recorded as he makes the check. Furthermore, this recording is accomplished in a neat, convenient manner and each check and voucher appears prepared for use, with no prior assembling necessary upon the part of the check maker. The voucher system also makes a convenient accessory for an accounting of expenditures and is sufficient for most individuals for summarizing for income tax purposes and the like.

As is apparent, the system also provides for an accurate system of recording expenditures, since an impression of the actual check is obtained and no errors can arise from transposition of figures in recording the amount for which a check was made.

While a preferred and specific form of the invention has been described along with various modifications, other modifications of this invention will be readily apparent and the invention is intended to be limited only by the scope of the appended claims and the prior art.

I claim:

1. A combined check and voucher unit formed from a single sheet of paper and comprising a rectangular check portion having an upper and a lower edge extending transversely of said sheet at right angles to opposite side edges thereof, said check portion having indicia and spaces within the upper half thereof for writing thereon the date, payee and amount of the check, and space within the lower half thereof for the maker's signature, a rectangular voucher portion having an upper and a lower edge, said check and voucher portions being of substantially the same size, said voucher portion being normally positioned beneath said check portion with said upper edges and said lower edges in register, said check and voucher portion being detachably secured together along said lower edges, said voucher portion having blank spaces in register with said check portion date, payee and amount spaces, a lined record column imprinted within the lower half of said voucher portion, a series of perforations adjacent a side edge of said voucher portion whereby the voucher portion when detached from said check portion may be

shingled with other like vouchers upon an accounting board, said sheet comprising a transfer portion detachably secured to said check portion upper edge, said transfer portion extending from said check portion by a distance substantially equal to one half the distance between said check portion upper and lower edges and being normally interleaved between said check and voucher portions whereby said transfer portion underlies only the upper half of said check portion, said transfer portion having a pressure sensitive transfer medium upon the surface thereof lying next adjacent said voucher portion for duplicating thereon the date, payee and amount of the check.

2. A combined check and voucher unit formed from a single sheet of paper and comprising a rectangular check portion having an upper and a lower edge extending transversely of said sheet at right angles to opposite side edges thereof, said check portion having indicia and spaces within the upper half thereof for writing thereon the date, payee and amount of the check, and space within the lower half thereof for the maker's signature, a rectangular voucher portion having an upper and a lower edge, said check and voucher portions being of substantially the same size, said voucher portion being normally positioned beneath said check portion with said upper edges and said lower edges in register, said check and voucher portion being detachably secured together along said lower edges, said voucher portion having blank spaces in register with said check portion date, payee and amount spaces, said sheet comprising a binding portion extending from the upper edge of said voucher portion and adapted for binding together a plurality of said units, said sheet comprising a transfer portion detachably secured to said check portion upper edge, said transfer portion extending from said check portion by a distance substantially equal to one half the distance between said check portion upper and lower edges and being normally interleaved between said check and voucher portions whereby said transfer portion underlies only the upper half of said check portion, said transfer portion having a pressure sensitive transfer medium upon the surface thereof lying next adjacent said voucher portion for duplicating thereon the date, payee and amount of the check.

3. A combination check and voucher unit comprising a rectangular sheet provided with an upper and a lower tear line, said tear lines extending parallel with each other and with the opposite end edges of said sheet and across the entire width thereof, the portion of said sheet between said tear lines defining a blank check portion and being provided with date, payee and amount lines adjacent to and par-

allel with said upper tear line and a signature line adjacent to and parallel with said lower tear line, a second portion of said sheet below said lower tear line normally folded back under said check portion, said second portion defining a voucher portion and being provided with blank spaces facing the reverse side of said check in the folded condition thereof in register with the spaces delineated by said date, payee and amount lines of said check portion, a third portion of said sheet immediately above said upper tear line being provided with a transfer coating on the same surface of said sheet as said check form and being normally folded about said upper tear line and extending between said check and voucher portions, the distance between said upper tear line and the adjacent upper edge of said third portion being not substantially greater than the distance between said upper tear line and said payee and amount lines, whereby in use said third portion will transfer the date, payee and amount as written on said check portion onto said voucher portion, but not the signature.

4. A combined check and voucher unit comprising an elongated rectangular voucher portion and an identically sized check portion superposed on said voucher portion in register therewith, said check and voucher portions being detachably secured together along one pair of the adjacent longitudinal edges thereof, indicia on said check portion within the longitudinal half thereof spaced most remotely from the said longitudinal edge thereof for recording thereon the date, payee and amount of the check, indicia on said voucher portion corresponding to and in register with said check portion indicia, the other longitudinal half of said check portion having a space thereon for the signature of the maker, and a transfer sheet interleaved between said check and voucher portions and positioned only beneath said first mentioned longitudinal half of said check portion, said transfer sheet having a pressure sensitive transfer medium upon the surface thereof lying next adjacent said voucher portion whereby the date, payee and amount of the check will be duplicated upon said voucher portion.
